UNITED STATES PATENT OFFICE.

ALEXANDER S. SPEER, OF CHICAGO, ILLINOIS.

ROOFING-SLAB.

1,318,238.

Specification of Letters Patent.

Patented Oct. 7, 1919.

Application filed April 7, 1919. Serial No. 288,035.

To all whom it may concern:

Be it known that I, ALEXANDER S. SPEER, a citizen of the United States, resident of Chicago, Illinois, have invented certain new and useful Improvements in Roofing-Slabs, of which the following is a specification.

My invention relates to shingle units, or strips, designed when laid in a roof to simulate a plurality of individual shingles.

0 The invention aims to provide from a sheet of roofing material of well known, or improved, construction which is of much greater length than width a plurality of shingle units, or strips, with a minimum of waste, and each unit of such form that when used to construct a roof in the usual way the end edges of the underlying portion of the unit will register with the intact portion of all of the overlying units, or strips, 0 and will not register with the cut-out portion thereof, or spaces between the projecting portions, or projections which simulate the individual shingles.

The invention includes the shingle units, 5 as will be hereinafter described and particularly pointed out in the appended claims.

The invention is illustrated in the accompanying drawings, in which:—

Figure 1 is a plan view of a sheet of roofing material with the lines of cutting for one form of shingle unit illustrated by dotted lines.

Fig. 2 is a plan view of a section of a roofing formed by the shingle units produced in the manner illustrated in Fig. 1.

Fig. 3 is a view similar to Fig 1, showing in dotted lines the lines of severance for producing a slightly different form of shingle unit, and,

0 Fig. 4 is a section of a roof formed by shingle units of the character produced in the manner indicated in Fig. 3.

A strip of roofing material of well known, or improved construction, and of materially greater length than width is designated 1 in Figs. 1 and 2. From a strip of this character a plurality of shingle units, as will be hereinafter described, are produced. The shingle unit, or strip, is designated 2

0 in Figs. 1 and 2, and 3 in Figs. 3 and 4, and in each instance it includes a front portion comprising a plurality of projections, or tongues, 2^a, 3^a, with intervening spaces which may be, as shown in Fig. 2, the same size and shape as the tongues, or which may

be, as shown in Fig. 4, of considerably less size. Each unit also includes a body portion 2^b, 3^b, which is of considerably greater width than the tongue and as shown in Figs. 2 and 4 is approximately twice as wide as 60 the tongue.

In forming a roof the units are laid in horizontal courses with the end edges of the units in each course abutting and with the courses so superimposed that the projections, 65 or tongues, of each course will be exposed in advance of the tongues, or projections, of the overlying course and with the middle of the spaces between the tongues, or projections, of the immediate underlying course in 70 register with the middle of the tongues, or the projections, of the immediate overlying course.

As the body portion of each unit is preferably twice as wide as the width of the 75 tongues throughout the major portion of a roof made up of these units, each course has two courses superimposed thereupon, as shown in Figs. 2 and 4.

In prior practice shingle units have been 80 made substantially of the construction described and have been used in constructing roofs substantially in the manner described and it has been the uniform practice in these articles of the prior art to have the end 85 edges of the body portion of the units disposed substantially perpendicular to the general line of the front edge of the blank, or perpendicular to the line of each horizontal course of blanks as laid in a roof, with 90 the result that portions of the abutting ends of contiguous units will register with the spaces between the projections of certain of the overlying units.

For instance, were the end edges of the 95 units, shown in Fig. 1, arranged perpendicular to the general line of the front edge of the unit, or perpendicular to the lines of the courses, portions of the abutting edges of the body portions of the blanks of the lowermost course would be in register with the spaces between the projections of the blanks forming the third course.

My invention aims to insure the covering of the lines of juncture between abutting 105 units by the intact portions of the units of both of the overlying courses, and the manner of accomplishing this object as disclosed herein consists in running the end edges of the body portions of the units at an angle 110

less than a right angle—and as shown herein, at an obtuse angle—to the general direction of the front line of the unit.

For producing a plurality of shingles having the described characteristic from a strip of roofing, such as that designated 1, and with a minimum of waste, I cut the units from the strip with the width of the units disposed substantially lengthwise of the strip, the length of the units being disposed substantially widthwise of the strip. The units are preferably made of such length that a pair of the same will correspond to the width of the strip 1 and the general line of severance forming the front and back of each unit extended other than at right angle to the lengthwise edge of the strip. As shown in Fig. 1, the general line of severance is at an obtuse angle to the lengthwise edges of the strip.

Thus, each lengthwise section of the strip 1 of a width corresponding to the maximum width of the shingle unit is designed to form a blank which, when severed through the middle, will provide two shingle units and this line of severance is along a line parallel to the side edges of the strip 1.

As shown in Fig. 1, the outer edges of the body portions of the units will be formed by the lengthwise edges of the strip 1 and due to the angle of the general line of severance forming the lengthwise edges of the blank the edges thereof formed by the lengthwise edges of the strip 1, as well as the edges formed by severing the blank through the middle, will be disposed at the desired angle to the general line of the lengthwise edges of the blanks.

In the exemplification of the invention shown in Fig. 3 the same general plan for

severing the units from the strip 1 is followed, but there is slightly more waste than in the plan illustrated in Fig. 1, due to the difference in the shape of the projections, or tongues, provided on the units.

Claims relating to the method herein described have been divided out from this case and included in a separate application, filed September 19, 1919.

I claim:

1. A shingle unit, or strip, adapted to be laid end to end in a roof to form a course and to have similar courses superimposed thereupon, said unit having along one edge a plurality of projections and spaces, said projections simulating a plurality of individual shingles when the unit is laid in a roof, and a body portion of greater width than the projections, the end edges of said body portion being disposed at other than a right angle to the general line of the front edge of the unit.

2. A shingle unit, or strip, adapted to be laid end to end in a roof to form a course and to have similar courses superimposed thereupon, said unit having along one edge a plurality of projections and spaces, said projections simulating a plurality of individual shingles when the unit is laid in a roof, and a body portion of greater width than the projections, the end edges of said body portion being disposed at an obtuse angle to the general line of the front edge of the unit.

In testimony whereof, I affix my signature.

ALEXANDER S. SPEER.
